UNITED STATES PATENT OFFICE.

OSCAR J. BACKUS, OF SAN FRANCISCO, CALIFORNIA.

IMPROVED NOZZLE FOR HOSE-PIPE.

Specification forming part of Letters Patent No. 82,676, dated October 6, 1868.

To all whom it may concern:

Be it known that I, OSCAR J. BACKUS, of the city and county of San Francisco, State of California, have invented an Improved Hose-Nozzle; and I do hereby declare the following description and accompanying drawings are sufficient to enable any person skilled in the art or science to which it most nearly appertains to make and use my said invention or improvements without further invention or experiment.

The nature of my invention is to provide a nozzle for irrigating-hose or other purposes, so constructed that the sprinkler and eduction-pipe will be combined in one and the same pipe or nozzle.

To accomplish this object the usual pipe is employed, with a sprinkler coupled or screwed to the end, having a hole through the center, through which the eduction-pipe passes. This pipe extends downward only to the stop-cock way, and at each side of it are pierced two holes. The stop-cock is hollow, and has a large opening at one side, and a small opening at the opposite side, with two openings still smaller about midway between the quarter, so that by turning the holes in the cock to correspond with the openings in the induction and eduction pipes, a single stream of water is thrown, and by turning the cock still farther the hole in the eduction-pipe is closed, and the water from the induction pipe or hose enters the barrel of the stop-cock, and passes through the two holes at the side of the eduction-pipe into the chamber of the nozzle and out through the sprinkler.

In order to more fully illustrate and explain my invention, reference is had to the accompanying drawings and letters marked thereon, of which—

Figure 1 is a side sectional elevation. Fig. 2 is a view of the cock. Fig. 3 is an end view.

A is the chamber in which the eduction-pipe B is placed, and is pierced at its base at each side of the pipe with two holes, C C,

which lead into the cock opening below. The cap or sprinkler D has an opening, D', and is screwed to the nozzle or chamber, the end of the eduction-pipe passing through the opening and projecting a short distance from the sprinkler, the opposite end leading into the cock-chamber.

The stop-cock is constructed with a barrel, and has a hole, E, at one side to correspond with the induction pipe or hose. Holes F G G, a little smaller in diameter than E, are also made at the top or opposite side of the cock, which correspond with those opening into the chamber and eduction-pipes from the cock-chamber, and when the opening F in the cock is turned so as to correspond with the opening through the pipe, water flows through in a single continuous stream, and when the cock is turned back a little this communication is cut off, and when turned so as to bring the two openings in the barrel of the cock in a line with the openings leading into the chamber of the nozzle, the water rushes into it, and out through the sprinkler.

Thus a sprinkler and a nozzle or pipe in one implement is had without the necessity of detaching or attaching parts in order to throw a single stream, or in a shower, as may be desired, the whole implement being constructed at an additional cost, amounting to but a trifle, above the ordinary nozzle.

Having thus described my invention, what I claim as new, and desire to secure by Letters Patent, is—

The combination, with a nozzle throwing a single stream of water, of the sprinkler D, constructed and operated with the holes E F G G in the stop-cock, and holes C C, leading into the nozzle-chamber, substantially as and for the purpose specified.

In witness whereof I have hereunto set my hand and seal.

OSCAR J. BACKUS. [L. S.]
